(57) **CLAIM**

The ornamental design for a robotic arm for medical purposes, as shown and described.

DESCRIPTION

FIG. 1 is a perspective view of a robotic arm for medical purposes showing our new design;

FIG. 2 is a right view of the article of FIG. 1;

FIG. 3 is a left view of the article of FIG. 1;

FIG. 4 is a front view of the article of FIG. 1;

FIG. 5 is a bottom view of the article of FIG. 1;

FIG. 6 is a top view of the article of FIG. 1;

FIG. 7 is a rear view of the article of FIG. 1; and,

FIG. 8 is a rear perspective view of the article of FIG. 1.

1 Claim, 8 Drawing Sheets
